(57) **CLAIM**

I claim the ornamental design for a display rack, as shown and described.

DESCRIPTION

FIG. 1 is a perspective view of a display rack;

FIG. 2 is a front view thereof;

FIG. 3 is a right side view thereof;

FIG. 4 is a top view thereof;

FIG. 5 is a bottom view thereof; and,

FIG. 6 is a left side view thereof.

The broken-line disclosure represent portions of the rack which form no part of the claimed design.

1 Claim, 6 Drawing Sheets*FIG. 1*

FIG. 2

FIG. 3

FIG. 4

FIG. 5

FIG. 6
